UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

FURNACE-WALL.

1,341,645.

Specification of Letters Patent. Patented June 1, 1920.

Application filed April 10, 1916. Serial No. 90,058.

To all whom it may concern:

Be it known that I, DAVID S. JACOBUS, a citizen of the United States, residing at Jersey City, in the county of Hudson and State of New Jersey, have invented certain new and useful Improvements in Furnace-Walls, of which the following is a specification.

The present invention relates to certain improvements in the construction of walls for boiler furnaces, and will be understood by reference to the accompanying drawings, in which Figure 1 is a vertical longitudinal section through a portion of a Babcock & Wilcox boiler provided with my improved wall construction; Fig. 2 is a front view partly in section, the section being on the plane of the line 2—2 of Fig. 1; Fig. 3 is a horizontal section on the line 3—3 of Fig. 2; Fig. 4 is an enlarged horizontal section of one form of the special refractory blocks with engaging pieces; Fig. 4^A is a view of a modified form of block; Fig. 5 is a partial elevation, partly broken away, showing the form of brick of Fig. 4; Fig. 6 is a side view of two courses of the refractory blocks showing the tie connections, the inner surfaces of the blocks being substantially flush with the inner surface of the wall; Fig. 7 is an end view of one of the tie pieces; Fig. 8 is a perspective view, partly broken away, and Fig. 9 is an end view, partly in section, showing the tie pieces placed horizontally instead of vertically. Similar reference numerals indicate similar parts in the several views.

To illustrate one application of my invention, I have shown it in connection with a Babcock & Wilcox boiler which comprises a bank of generating tubes 1 expanded into front and rear headers 2 and 3, respectively. The boiler is shown as fired with an under-feed stoker of well known construction. The brickwork of the front wall 5 of the furnace rests upon the stoker ledge plate, said plate consisting of the top plates 4 of the fuel magazines or retorts 4' between the twyer boxes 6' and the top plates 6 of said boxes, which rest upon the retort plates, the wall thus terminating at the upper parts of the stoker mechanism. The parts which form the sides of the retorts and twyer boxes have integral webs 4² which rest upon inner struts 7 beneath the front wall. The plates 4 are supported upon the sides of the re-

torts, and the plates 6 are, in turn, supported upon plates 4. Thus the struts assist in supporting the wall. The struts 7 rest upon beams 8 and are spaced at intervals across the front of the stoker so that they do not interfere with the stoker mechanism. The longer outer struts 7² are simply to support the outer parts of the stoker. I do not claim herein the construction just described, as the same is covered in other patent applications.

To maintain the alignment of the front wall and to prevent movement thereof inward or outward, I build a part of the wall of one or more horizontal courses which have refractory blocks 9 therein, said blocks having recesses 10 in the sides thereof, as shown in Fig. 4. I lay one or more courses of these special blocks in the wall and when more than one course is used I, preferably interlock them by means of metallic tie pieces 11 of general T-form, as shown in Fig. 7, having lateral flanges or side extensions of the T-heads 12 which fit the recesses 10 in the tiles. These tie pieces are also provided at their outer portions with extensions 12² forming lugs adapted to be engaged by the inner flanges of Z-bars 13 secured in a horizontal position to the inner face of the front casing 14. The tie pieces are placed in position by moving them outwardly from the inside of the furnace chamber and then turning them vertically into position where their lugs engage the Z-bar flanges. The blocks 9 are placed into position between the tie pieces 11 so that when the wall is completed the recesses of the blocks are engaged by the T-heads 12 of the tie pieces, and the ends of the tie pieces project above and below the courses, as shown in Fig. 8. The blocks are reduced slightly in width at the ends which engage the tie pieces so as to provide proper spaces for the webs of the tie pieces. The tie pieces 11 may slide horizontally along the Z-bars, thus allowing sidewise expansion of the courses formed by the blocks. The expansion of the wall in a vertical direction will cause the blocks to slide vertically over the tie pieces, and the tie pieces may also shift vertically. The wall may be completed by adding tiling or rows of ordinary fire-brick above the special blocks 9 if desired, as shown in Fig. 8.

The front portions of the tie pieces 11, with their lugs 12², extend into the space

between the casing 14 and the front faces of the blocks 9, the blocks being preferably so set that their front faces are flush with the surfaces of the portions of the bricks 5 below and above the blocks 9, as shown in Fig. 8. This permits the insertion of the tie pieces 11 and the making of repairs from inside the furnace chamber without removing any portion of the metallic front 10 casing 14.

If it is found necessary to replace some of the blocks 9 near the middle of the course, one block will be chipped out from inside the furnace chamber and removed, 15 and then all of the remaining blocks may be removed by sliding each of them sidewise until the lateral flange of the T-heads 12 of the tie piece 11 is cleared, when the block may be withdrawn. Similarly, the blocks 20 may be replaced from inside the furnace chamber, each block being moved toward the front and then sidewise until a flange 12 is engaged in the recess 10 in the block. The last block to be inserted will have its 25 side edges between the front of the block and the recess 10 chipped away so that the block may be slid into place. Contact between the side of the flange 12 and the block will hold the adjacent tie pieces in place and 30 thus lock the whole course in position.

In Fig. 4^a I show a modified form of block, in which the engaging groove 10^a for the tie pieces is in the body of the block.

In Fig. 8 the upper parts of the wall 35 comprising the special blocks is shown as racked over in two steps instead of racked over in a single step, as in Fig. 1.

From the foregoing description, it will be seen that any tendency of the wall to 40 lean inward will be resisted by the casing 14, by reason of the lugs 12^a engaging with the Z-bars 13 rigidly secured to said casing. Any outward movement will, of course, be resisted by the casing itself.

In many cases it is not necessary to use 45 the steel casing 14 shown in Figs. 1 and 8; and the wall may be supported in other ways than that shown in Fig. 1. In the structure shown in Fig. 6, the tie pieces 50 are held by two cross-members 15 in the form of I-bars with no outer wall casing. These I-bars serve to prevent the wall from moving inward, and, at the same time, resist outward movement.

In the structure illustrated in Fig. 9, the 55 tie pieces 11 are placed horizontally instead of vertically, and three courses of the special refractory blocks are shown laid up with a wall of the same width as the usual 60 blocks. The members 16 against which the projecting ends or lugs of the tie pieces 11 are made to rest are run vertically instead of horizontally. As the tie pieces 11 may slide along the members 16, the ex-

pansion of the wall upward cannot cause 65 an undue strain. Any sidewise expansion of the wall will cause the tiles 9 to slip over the heads of the tie pieces 11, which again prevents undue strains being brought to bear on the tie pieces or brickwork. 70

What I claim is:—

1. A vertically extending furnace wall built up of courses of blocks, one or more of the courses having grooved or recessed blocks, a fixed member and metallic tie 75 pieces engaging the fixed member and the grooves or recesses of the blocks and arranged to allow the blocks to move in any direction in a generally vertical plane, the tie pieces assisting in holding the wall in 80 proper alinement.

2. A vertically extending furnace wall built up of courses of blocks, one or more of the courses having grooved or recessed blocks, a fixed member and metallic tie 85 pieces engaging the fixed member and the grooves or recesses of the blocks and arranged to allow the blocks to move in any direction in a generally vertical plane, the tie pieces assisting in holding the wall in 90 proper alinement, and an outer wall casing having portions engaging the metallic tie pieces.

3. A vertically extending furnace wall built up of courses of blocks, one or more of the courses having grooved or recessed blocks, a fixed member, and vertically extending metallic tie pieces engaging the fixed member and the grooves or recesses of the blocks and arranged to allow the blocks 100 to move in any direction in a generally vertical plane, the tie pieces aiding to hold the wall in proper alinement.

4. A steam boiler furnace having a vertically extending wall with an opening at the 105 bottom thereof, means beneath the wall at the opening to support the wall above the opening, a fixed member and tie pieces in the wall and engaging the fixed member and arranged to allow the wall to move in any 110 direction in a generally vertical plane and to assist in maintaining the wall in alinement.

5. A furnace wall comprising one or more courses having grooved or recessed blocks, a 115 fixed member, metallic tie pieces laid alternately with the blocks and engaging the grooves or recesses and the fixed member to assist in holding the wall in alinement, and a plurality of vertical, spaced-apart struts 120 assisting to support the wall.

6. A furnace comprising one or more courses having grooved or recessed blocks, a fixed member, metallic tie pieces engaging the grooves or recesses and the fixed member 125 to assist in holding the wall in alinement while allowing relatively free movement of the wall in any direction in a generally ver-

45

tical plane, and a plurality of vertical, spaced-apart struts assisting to support the wall.

7. A steam boiler furnace having a front wall, a stoker mechanism upon a part of which the wall rests, and a plurality of struts underneath the stoker mechanism for supporting the same and the wall superimposed thereon, at least a portion of the front wall having means for holding it against inward bulging.

8. A steam boiler furnace having a front wall, a stoker mechanism upon a part of which said wall rests, and a plurality of struts underneath the stoker mechanism for supporting the same and the wall superimposed thereon, the wall having means for holding it against either inward or outward movement.

20 9. A steam boiler furnace having a vertically extending front wall, a stoker upon a part of which the wall rests, a fixed member, grooved or recessed blocks in the wall, and tie pieces engaging the fixed member 25 and the grooves or recesses and arranged to allow the blocks to move in any direction in a generally vertical plane and to assist in maintaining the wall in alinement.

10. A boiler furnace having a front wall, 30 a stoker mechanism extending under the wall, and the wall resting thereon, a plurality of vertical struts for reinforcing the stoker and aiding in supporting the wall, and means engaging the wall for holding it 35 in alinement above the stoker mechanism.

11. A steam boiler furnace having a front wall, a plurality of spaced-apart stoking mechanisms operating beneath the wall, the lower part of the wall terminating at the 40 upper part of the stoking mechanism, a plurality of vertical, spaced-apart struts assisting to support the wall, a fixed member and

metallic tie pieces in the wall and engaging with the fixed member to assist in holding the wall in alinement.

50

12. A steam boiler furnace having a front wall comprising one or more courses having grooved or recessed blocks, a fixed member, metallic tie pieces engaging the grooves or recesses of the blocks and engaging with the fixed member to assist in holding the wall in alinement, a plurality of spaced-apart stoking mechanisms operating beneath the wall, and a plurality of vertical, spaced-apart struts assisting to support the wall.

55

13. A steam boiler furnace having a front wall, a plurality of spaced-apart stoking mechanisms comprising retorts and twyer boxes, a part of the wall resting on the mechanisms, a fixed member, metallic tie pieces in the wall and engaging with the fixed member to assist in holding the wall in alinement, and a plurality of spaced-apart struts beneath the twyer boxes assisting to support the wall.

60

14. A steam boiler furnace having a front wall, a plurality of spaced-apart stoking mechanisms operating beneath the wall and a plurality of vertical struts located in the spaces between the separated stoker mechanisms and assisting to support the wall, a fixed member, and metallic tie pieces in the wall and engaging the fixed member to assist in holding the wall in alinement while allowing movement of the wall in any direction in a generally vertical plane.

70

75

In testimony whereof I have hereunto signed my name in the presence of two subscribing witnesses.
